GLASS CHROMATOGRAPHIC SPRAY UNIT

Joseph Kopp, Jackson Heights, N.Y.

Application January 8, 1959, Serial No. 54,092

Term of patent 14 years

(CL. D16—1)

Fig. 1 is a side elevational view of a glass chromatographic spray unit, showing my new design;

Fig. 2 is a similar view taken from the right of Fig. 1; and

Figure 3 is a top perspective view thereof.

I claim:

The ornamental design for a glass chromatographic spray unit, substantially as shown.
